UNITED STATES PATENT OFFICE.

ALONZO C. RAYMOND, OF DETROIT, MICHIGAN.

APPARATUS FOR PARTITION CONSTRUCTION.

No. 861,767.

Specification of Letters Patent.

Patented July 30, 1907.

Application filed June 21, 1905. Serial No. 266,218.

To all whom it may concern:

Be it known that I, ALONZO C. RAYMOND, a citizen of the United States, residing at Detroit, county of Wayne, State of Michigan, have invented a certain 5 new and useful Improvement in Apparatus for Partition Construction; and declare the following to be a full, clear, and exact description of the same, such as will enable others skilled in the art to which it pertains to make and use the same, reference being had to the accompanying drawings, which form a part of this specification.

My invention relates to apparatus adapted for partition construction, and especially that form of construction embodied in an application heretofore filed by me 15 and now pending under Serial No. 258,891, and it consists in the various details, arrangements and combinations hereinafter described and claimed.

In the drawings:—Figure 1, illustrates a partition in the process of construction, in which is employed the 20 leveling and truing apparatus hereinabove described. Fig. 2, is a sectional view of vertical tiles held in place by a straight edge, and its supports, and spaced by a clamp. Fig. 3, is a perspective of the funnel employed to guide the staff between the layers of tile when columns are formed. Fig. 4, is a perspective of the funnel in place between tiles. Fig. 5, illustrates the spring clamp for spacing tiles. Fig. 6, shows the spring clamp by which the tiles are held to the straight edges. Fig. 7, shows in detail the bracket on which the straight 25 edges are supported. Fig. 8, shows the metal clasp or bond by which the parallel rows of tile are held apart at uniform distance, pending the introduction of a funnel to form a staff column.

In the drawings, A, A, represents a partition in process of construction, the partition is composed of building tile, a, a, upon either side thereof; erected in parallel planes and between the tile is a space of suitable dimensions. The posts C form a standard which is plumbed in place and upon which are sliding brackets 30 or arms, D, D. Two or more of the operating posts C, are used to hold an equal number of brackets. The sliding brackets D, D, upon each of these posts support straight edges made of board or plank, G, G¹, the lower straight edge G rests on the inturned lower end of the brackets D; between the inturned ends of the 35 brackets D; a clamp block 2 with space below it for the straight edge, and space above it under the inturned upper end of the bracket for the upper straight edge G¹; the block 2 is held to the post C (preferably with an interposed wedge 3) by a double hook 4. In erecting this 40 structure, the post C is brought in contact with the ceiling joist or other convenient portion of the structure above it and roughly adjusted thereto, approximately

filling the distance between the floor and ceiling. It is then plumbed, so that the partition that is to be erected 55 adjacent thereto shall be straight and true when completed; a pair of straight edges supported on brackets are clamped to the standards. A series of tile are then laid edgewise, with their faces resting squarely against the straight edges G, G¹, and held firmly thereto by the 60 spring holding device shown in Fig. 6. Another series of tile properly spaced therefrom by means of the spacer hereinafter described is then erected, and attached to the first series by metal ties, (Fig. 8) preferably of copper or steel. It is obvious that by so erecting them in 65 connection with the edge of the lowermost straight edge G; the partition, to the extent of the length of the straight edge, will be straight, and it is further obvious that if the straight edge G, be carried up when additional rows of tile are laid, the partition will not only be 70 straight longitudinally but will be vertically perpendicular or in a plane parallel to the plane of the posts C.

The two sets of tile are brought to a parallel position by the tool shown in Fig. 5, which acting in conjunction with the straight edges, places the outer layer of tile 75 perfectly true with the inner layer and thus the whole partition is true. This tool consists of a clamp P, having depending projections, p, p; these are spaced the proper distance apart and rigidly formed with the clamp P, to engage outside the two surfaces of the tile. 80 Two levers marked 5, 5, pass through a mortise in the clamp and are pivoted therein, by pins 6. The lower ends 7, 7, of the levers 5, 5, are normally spread by spring 8, and are adapted to hold the edges of the tile in place as shown in Fig. 2. Inasmuch as the inner 85 tile M, is in contact with the straight edge G, it follows that the outer tile N, will be spaced accurately therefrom and variations in the thickness of the tile will make no difference as to the total thickness of the partition or the spacing of the outside surfaces. In order 90 to hold the tile M, and the tile N, thus spaced up to the straight edge, I employ a spring hook T; (shown in Fig. 6); one prong t, hooks over the straight edge and the other one t', over the outer tile, thus holding the straight edge and the tile firmly together until the 95 structure is completed and set, as hereinafter described.

When the tiles are spaced properly, I secure them in that position by metal ties or clasps b, of the proper length, and erect a second tier of tile upon the lower one and continue until a proper height is reached, for 100 the introduction of the funnel 10, for the construction of the column of adhesive material which permanently binds together the two series of tiles.

At any suitable height and at suitable intervals in the horizontal length of the partition, I insert a funnel 10; 105 the upper end of this frame is rectangular with flaring

sides, as shown at U. Depending from the mouth part are two strips 11, 11, preferably of metal; these strips are substantially equal in width to the distances between the tile. The strips are of a length to pass 5 one or more rows of tile. These strips are also provided with one or more hinges by means of which they can be inserted and be removed from between the rows of tiles as they approach the ceiling or the bottoms of window frames or other places where the structure 10 terminates. At suitable intervals this funnel is inserted between the rows of tile or blocks, and staff, which is a mixture of adhesive material and fiber, and is used in a semi-liquid form, and adapted to set or solidify, is poured through the funnel 10; the staff en- 15 engages with the inside faces of the tile and while the funnel is still in place it is firmly, but rather gently rammed until there are no cavities; it is then allowed to set; the staff soon sets to a consistency such that the funnel may be withdrawn. After the staff has fully set, 20 it adheres firmly to the tile and binds the two rows of the tile together. At suitable points, blocks of wood may be placed in the staff and forced down to the proper places, as shown at 12, Fig. 4, and base boards, or other finishing material may be nailed thereto on either side 25 by driving the nails through the tile and into the blocks of wood in either direction. The blocks become embedded in the column of staff and are perfectly surrounded by fire-proof material, wood not coming in contact with wood at any point. It will be 30 noted that while these devices for constructing such a partition or wall are separate in themselves, yet they are used in conjunction until the columns of staff are set, then they are removed and the straight edges are moved away from contact with the partition or wall, 35 and then by loosening the clamps which hold the sliding brackets or arms to the post, they are moved upward carrying the straight edges into the proper position for the erection of another series of tiles or

blocks, until the partition or wall is completed and finished by hand at the top.

40

What I claim is:—

1. Apparatus for wall construction, consisting of a funnel having independent jointed sides adapted to engage with their lateral edges the inner surfaces of a partition, and together therewith to confine in a column during its 45 period of plasticity adhesive material poured thereinto, substantially as described.

2. In tile wall construction, a funnel having independent hanging sides whereby adhesive material may be poured in between the inner surfaces of the partition and confined 50 between said hangers and binding columns formed therein, substantially as described.

3. A funnel, with independent hanging sides for insertion between parallel rows of blocks, or tiles, to form therein a column of adhesive material, binding said rows together, substantially as described.

4. A funnel with independent hinged sides for insertion between parallel rows of blocks, or tiles, to form therein a column of adhesive material, binding said rows together, substantially as described.

5. A funnel having strips hanging therefrom adapted to be placed at right angles to the surface of a vertical structure and to coöperate therewith in confining a staff column while in a fluid condition, substantially as described.

6. In wall construction, in combination with a funnel having parallel depending side portions adapted to simultaneously engage the inner faces of the surface members of said wall and to confine within specified limits the component material of the center portion of the wall during its period of plasticity, substantially as described.

7. In wall construction, in combination with a pouring funnel adapted to engage between opposite surface blocks of a wall provided with air spaces in the center portion thereof, folding depending sides therefor adapted to confine within predetermined limits a column of plastic material poured between said surface blocks, until the same has hardened, substantially as described.

In testimony whereof, I sign this specification in the presence of two witnesses.

ALONZO C. RAYMOND.
